CLAIM

The ornamental design for a jar sealer, as shown and described.

DESCRIPTION

FIG. 1 is a top perspective view of a jar sealer, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a bottom perspective of the jar sealer in an open state of use for ease of illustration.

The broken lines in the drawings illustrate the portions of the jar sealer, which form no part of the claimed design.

1 Claim, 9 Drawing Sheets
